US009885507B2

(12) **United States Patent**
Pham

(10) **Patent No.:** **US 9,885,507 B2**
(45) **Date of Patent:** **Feb. 6, 2018**

(54) **PROTECTION AND DIAGNOSTIC MODULE
FOR A REFRIGERATION SYSTEM**

(71) Applicant: **Emerson Climate Technologies, Inc.**,
Sidney, OH (US)

(72) Inventor: **Hung M. Pham**, Dayton, OH (US)

(73) Assignee: **Emerson Climate Technologies, Inc.**,
Sidney, OH (US)

(*) Notice: Subject to any disclaimer, the term of this
patent is extended or adjusted under 35
U.S.C. 154(b) by 662 days.

(21) Appl. No.: **14/080,473**

(22) Filed: **Nov. 14, 2013**

(65) **Prior Publication Data**

US 2014/0069121 A1 Mar. 13, 2014

(57) **ABSTRACT**

A system is provided and may include a compressor functioning in a refrigeration circuit. An ambient temperature sensor may produce a signal indicative of an ambient temperature. Processing circuitry may calculate an energy efficiency rating of the refrigeration circuit and may generate a relationship of the calculated energy efficiency rating and ambient temperature. The processing circuitry may compare the calculated energy efficiency rating to a base energy efficiency rating to determine if a fault condition exists.

PROTECTION AND DIAGNOSTIC MODULE
FOR A REFRIGERATION SYSTEMCROSS-REFERENCE TO RELATED
APPLICATIONS

This application is a continuation of U.S. patent application Ser. No. 11/776,879, filed on Jul. 12, 2007, which claims the benefit of U.S. Provisional Application No. 60/831,755, filed on Jul. 19, 2006. The disclosures of the above applications are incorporated herein by reference.

FIELD

The present disclosure relates to compressors, and more particularly, to a diagnostic system for use with a compressor.

BACKGROUND

The statements in this section merely provide background information related to the present disclosure and may not constitute prior art.

Compressors are used in a wide variety of industrial and residential applications to circulate refrigerant within a refrigeration, heat pump, HVAC, or chiller system (generically referred to as "refrigeration systems") to provide a desired heating and/or cooling effect. In any of the foregoing applications, the compressor should provide consistent and efficient operation to ensure that the particular refrigeration system functions properly.

Refrigeration systems and associated compressors may include a protection system that intermittently restricts power to the compressor to prevent operation of the compressor and associated components of the refrigeration system (i.e., evaporator, condenser, etc.) when conditions are unfavorable. The types of faults that may cause protection concerns include electrical, mechanical, and system faults. Electrical faults typically have a direct effect on an electrical motor associated with the compressor, while mechanical faults generally include faulty bearings or broken parts. Mechanical faults often raise a temperature of working components within the compressor, and thus, may cause malfunction of, and possible damage to, the compressor.

In addition to electrical faults and mechanical faults associated with the compressor, the compressor and refrigeration system components may also be affected by system faults attributed to system conditions such as an adverse level of fluid disposed within the system or to a blocked-flow condition external to the compressor. Such system conditions may raise an internal compressor temperature or pressure to high levels, thereby damaging the compressor and causing system inefficiencies and/or failures. To prevent system and compressor damage or failure, the compressor may be shut down by the protection system when any of the aforementioned conditions are present.

Conventional protection systems typically sense temperature and/or pressure parameters as discrete switches and interrupt power supplied to the electrical motor of the compressor should a predetermined temperature or pressure threshold be exceeded. Typically, a plurality of sensors are required to measure and monitor the various system and compressor operating parameters. With each parameter measured, at least one sensor is typically required, and therefore results in a complex protection system in which many sensors are employed.

2

Sensors associated with conventional protection systems are required to quickly and accurately detect particular faults experienced by the compressor and/or system. Without such plurality of sensors, conventional systems would merely shut down the compressor when a predetermined threshold mode and/or current is experienced. Repeatedly shutting down the compressor whenever a fault condition is experienced results in frequent service calls and repairs to the compressor to properly diagnose and remedy the fault. In this manner, while conventional protection devices adequately protect a compressor and system to which the compressor may be tied, conventional protection systems fail to precisely indicate a particular fault and often require a plurality of sensors to diagnose the compressor and/or system.

SUMMARY

A system is provided and may include a compressor functioning in a refrigeration circuit. An ambient temperature sensor may produce a signal indicative of an ambient temperature. Processing circuitry may calculate an energy efficiency rating of the refrigeration circuit and may generate a relationship of the calculated energy efficiency rating and ambient temperature. The processing circuitry may compare the calculated energy efficiency rating to a base energy efficiency rating to determine if a fault condition exists.

In another configuration, a system may include a compressor functioning in a refrigeration circuit. An ambient temperature sensor may produce a signal indicative of an ambient temperature. Processing circuitry may calculate an energy efficiency rating of the refrigeration circuit and may generate an efficiency index by dividing the calculated energy efficiency rating by the last stored value of the calculated energy efficiency rating for a particular ambient temperature to determine changes in efficiency of the refrigeration circuit over time.

A method is provided and may include producing a signal indicative of an ambient temperature, calculating by processing circuitry an energy efficiency rating of a refrigeration circuit, and generating by the processing circuitry a relationship of the calculated energy efficiency rating and ambient temperature. The method may also include comparing by the processing circuitry the calculated energy efficiency rating to a base energy efficiency rating and determining by the processing circuitry if a fault condition exists based on the comparison.

Further areas of applicability will become apparent from the description provided herein. It should be understood that the description and specific examples are intended for purposes of illustration only and are not intended to limit the scope of the present disclosure.

DRAWINGS

The drawings described herein are for illustration purposes only and are not intended to limit the scope of the present disclosure in any way.

FIG. 1 is a perspective view of a compressor incorporating a protection system in accordance with the principles of the present teachings;

FIG. 2 is a cross-sectional view of the compressor of FIG. 1;

FIG. 3 is a schematic representation of a refrigeration system incorporating the compressor of FIG. 1;

FIG. 4 is a table illustrating various sensor combinations used to detect specific fault conditions;

FIG. 5 is a flow chart depicting a process for determining system energy efficiency;

FIG. 6 is a graph of current drawn by a compressor versus condenser temperature for use in determining condenser temperature at a given evaporator temperature;

FIG. 7 is a graph of discharge temperature versus evaporator temperature for use in determining an evaporator temperature at a given condenser temperature;

FIG. 8 is a graph of discharge superheat versus suction superheat to determine suction superheat at a given outdoor/ambient temperature;

FIG. 9 is a graph of energy efficiency versus outdoor/ambient temperature for use in diagnosing a compressor and/or refrigeration system;

FIG. 10 is a flowchart illustrating a procedure used to determine system load and energy consumption of a refrigeration system;

FIG. 11 is a table illustrating various sensor combinations used to detect specific fault conditions;

FIG. 12 is a graph depicting specific fault conditions at various discharge superheat conditions;

FIG. 13 is a flowchart depicting a process for installing and diagnosing a compressor and/or refrigeration system;

FIG. 14 is a flowchart depicting a compressor installation process;

FIG. 15 is a flowchart depicting a compressor installation and refrigerant-charge process;

FIG. 16 is a graphical representation of various system and compressor faults based on condenser temperature difference and discharge superheat progressions;

FIG. 17 is a graphical representation of subcooling, condenser temperature difference, discharge superheat, energy efficiency rating, and capacity for use in determining a charge level of a refrigeration system;

FIG. 18 is a flowchart illustrating a process for verifying air flow through an evaporator; and

FIG. 19 is a flowchart illustrating a process for verifying a refrigerant charge of a refrigeration system.

DETAILED DESCRIPTION

The following description is merely exemplary in nature and is not intended to limit the present disclosure, application, or uses. It should be understood that throughout the drawings, corresponding reference numerals indicate like or corresponding parts and features.

With reference to the drawings, a compressor 10 is shown incorporated into a refrigeration system 12. A protection and control system 14 is associated with the compressor 10 and the refrigeration system 12 to monitor and diagnose both the compressor 10 and the refrigeration system 12. The protection and control system 14 utilizes a series of sensors to determine non-measured operating parameters of the compressor 10 and/or refrigeration system 12. The protection and control system 14 uses the non-measured operating parameters in conjunction with measured operating parameters from the sensors to diagnose and protect the compressor 10 and/or refrigeration system 12.

With particular reference to FIGS. 1 and 2, the compressor 10 is shown to include a generally cylindrical hermetic shell 15 having a welded cap 16 at a top portion and a base 18 having a plurality of feet 20 welded at a bottom portion. The cap 16 and the base 18 are fitted to the shell 15 such that an interior volume 22 of the compressor 10 is defined. The cap 16 is provided with a discharge fitting 24, while the shell 15 is similarly provided with an inlet fitting 26, disposed generally between the cap 16 and base 18, as best shown in

FIG. 2. In addition, an electrical enclosure 28 is fixedly attached to the shell 15 generally between the cap 16 and the base 18 and operably supports a portion of the protection and control system 14 therein.

5 A crankshaft 30 is rotatably driven by an electric motor 32 relative to the shell 15. The motor 32 includes a stator 34 fixedly supported by the hermetic shell 15, windings 36 passing therethrough, and a rotor 38 press-fit on the crankshaft 30. The motor 32 and associated stator 34, windings 36, and rotor 38 cooperate to drive the crankshaft 30 relative to the shell 15 to compress a fluid.

The compressor 10 further includes an orbiting scroll member 40 having a spiral vein or wrap 42 on an upper surface thereof for use in receiving and compressing a fluid.

15 An Oldham coupling 44 is disposed generally between the orbiting scroll member 40 and bearing housing 46 and is keyed to the orbiting scroll member 40 and a non-orbiting scroll member 48. The Oldham coupling 44 transmits rotational forces from the crankshaft 30 to the orbiting scroll member 40 to compress a fluid disposed generally between the orbiting scroll member 40 and the non-orbiting scroll member 48. Oldham coupling 44, and its interaction with orbiting scroll member 40 and non-orbiting scroll member 48, is preferably of the type disclosed in assignee's commonly owned U.S. Pat. No. 5,320,506, the disclosure of which is incorporated herein by reference.

20 Non-orbiting scroll member 48 also includes a wrap 50 positioned in meshing engagement with the wrap 42 of the orbiting scroll member 40. Non-orbiting scroll member 48 has a centrally disposed discharge passage 52, which communicates with an upwardly open recess 54. Recess 54 is in fluid communication with the discharge fitting 24 defined by the cap 16 and a partition 56, such that compressed fluid exits the shell 15 via discharge passage 52, recess 54, and fitting 24. Non-orbiting scroll member 48 is designed to be mounted to bearing housing 46 in a suitable manner such as disclosed in assignee's commonly owned U.S. Pat. Nos. 4,877,382 and 5,102,316, the disclosures of which are incorporated herein by reference.

25 30 35 40 The electrical enclosure 28 includes a lower housing 58, an upper housing 60, and a cavity 62. The lower housing 58 is mounted to the shell 15 using a plurality of studs 64, which are welded or otherwise fixedly attached to the shell 15. The upper housing 60 is matingly received by the lower housing 58 and defines the cavity 62 therebetween. The cavity 62 is positioned on the shell 15 of the compressor 10 and may be used to house respective components of the protection and control system 14 and/or other hardware used to control operation of the compressor 10 and/or refrigeration system 12.

45 50 55 60 With particular reference to FIG. 2, the compressor 10 includes an actuation assembly 65 that selectively separates the orbiting scroll member 40 from the non-orbiting scroll member 48 to modulate a capacity of the compressor 10 between a reduced-capacity mode and a full-capacity mode. The actuation assembly 65 may include a solenoid 66 connected to the orbiting scroll member 40 and a controller 68 coupled to the solenoid 66 for controlling movement of the solenoid 66 between an extended position and a retracted position.

55 65 60 Movement of the solenoid 66 into the extended position separates the wraps 42 of the orbiting scroll member 40 from the wraps 50 of the non-orbiting scroll member 48 to reduce an output of the compressor 10. Conversely, movement of the solenoid 66 into the retracted position moves the wraps 42 of the orbiting scroll member 40 closer to the wraps 50 of the non-orbiting scroll member 48 to increase an output

of the compressor. In this manner, the capacity of the compressor **10** may be modulated in accordance with demand or in response to a fault condition. While movement of the solenoid **66** into the extended position is described as separating the wraps **42** of the orbiting scroll member **40** from the wraps **50** of the non-orbiting scroll member **48**, movement of the solenoid **66** into the extended position could alternately move the wraps **42** of the orbiting scroll member **40** into engagement with the wraps **50** of the non-orbiting scroll member **48**. Similarly, while movement of the solenoid **66** into the retracted position is described as moving the wraps **42** of the orbiting scroll member **40** closer to the wraps **50** of the non-orbiting scroll member **48**, movement of the solenoid **66** into the retracted position could alternately move the wraps **42** of the orbiting scroll member **40** away from the wraps **50** of the non-orbiting scroll member **48**. The actuation assembly **65** may be of the type disclosed in assignee's commonly owned U.S. Pat. No. 6,412,293, the disclosure of which is incorporated herein by reference.

With particular reference to FIG. 3, the refrigeration system **12** is shown to include a condenser **70**, an evaporator **72**, and an expansion device **74** disposed generally between the condenser **70** and the evaporator **72**. The refrigeration system **12** also includes a condenser fan **76** associated with the condenser **70** and an evaporator fan **78** associated with the evaporator **72**. Each of the condenser fan **76** and the evaporator fan **78** may be variable-speed fans that can be controlled based on a cooling and/or heating demand of the refrigeration system **12**. Furthermore, each of the condenser fan **76** and evaporator fan **78** may be controlled by the protection and control system **14** such that operation of the condenser fan **76** and evaporator fan **78** may be coordinated with operation of the compressor **10**.

In operation, the compressor **10** circulates refrigerant generally between the condenser **70** and evaporator **72** to produce a desired heating and/or cooling effect. The compressor **10** receives vapor refrigerant from the evaporator **72** generally at the inlet fitting **26** and compresses the vapor refrigerant between the orbiting scroll member **40** and the non-orbiting scroll member **48** to deliver vapor refrigerant at discharge pressure at discharge fitting **24**.

Once the compressor **10** has sufficiently compressed the vapor refrigerant to discharge pressure, the discharge-pressure refrigerant exits the compressor **10** at the discharge fitting **24** and travels within the refrigeration system **12** to the condenser **70**. Once the vapor enters the condenser **70**, the refrigerant changes phase from a vapor to a liquid, thereby rejecting heat. The rejected heat is removed from the condenser **70** through circulation of air through the condenser **70** by the condenser fan **76**. When the refrigerant has sufficiently changed phase from a vapor to a liquid, the refrigerant exits the condenser **70** and travels within the refrigeration system **12** generally towards the expansion device **74** and evaporator **72**.

Upon exiting the condenser **70**, the refrigerant first encounters the expansion device **74**. Once the expansion device **74** has sufficiently expanded the liquid refrigerant, the liquid refrigerant enters the evaporator **72** to change phase from a liquid to a vapor. Once disposed within the evaporator **72**, the liquid refrigerant absorbs heat, thereby changing from a liquid to a vapor and producing a cooling effect. If the evaporator **72** is disposed within an interior of a building, the desired cooling effect is circulated into the building to cool the building by the evaporator fan **78**. If the evaporator **72** is associated with a heat-pump refrigeration system, the evaporator **72** may be located remote from the

building such that the cooling effect is lost to the atmosphere and the rejected heat experienced by the condenser **70** is directed to the interior of the building to heat the building. In either configuration, once the refrigerant has sufficiently changed phase from a liquid to a vapor, the vaporized refrigerant is received by the inlet fitting **26** of the compressor **10** to begin the cycle anew.

With particular reference to FIGS. 2 and 3, the protection and control system **14** is shown to include a high-side sensor **80**, a low-side sensor **82**, a liquid-line temperature sensor **84**, and an outdoor/ambient temperature sensor **86**. The protection and control system **14** also includes processing circuitry **88** and a power-interruption system **90**, each of which may be disposed within the electrical enclosure **28** mounted to the shell **15** of the compressor **10**. The sensors **80, 82, 84, 86** cooperate to provide the processing circuitry **88** with sensor data for use by the processing circuitry **88** in determining non-measured operating parameters of the compressor **10** and/or refrigeration system **12**. The processing circuitry **88** uses the sensor data and the determined non-measured operating parameters to diagnose the compressor **10** and/or refrigeration system **12** and selectively restricts power to the electric motor of the compressor **10** via the power-interruption system **90**, depending on the identified fault.

The high-side sensor **80** generally provides diagnostics related to high-side faults such as compressor mechanical failures, motor failures, and electrical component failures such as missing phase, reverse phase, motor winding current imbalance, open circuit, low voltage, locked rotor current, excessive motor winding temperature, welded or open contactors, and short cycling. The high-side sensor **80** may be a current sensor that monitors compressor current and voltage to determine and differentiate between mechanical failures, motor failures, and electrical component failures. The high-side sensor **80** may be mounted within the electrical enclosure **28** or may alternatively be incorporated inside the shell **15** of the compressor **10** (FIG. 2). In either case, the high-side sensor **80** monitors current drawn by the compressor **10** and generates a signal indicative thereof, such as disclosed in assignee's commonly owned U.S. Pat. No. 6,615,594, U.S. patent application Ser. No. 11/027,757 filed on Dec. 30, 2004 and U.S. patent application Ser. No. 11/059,646 filed on Feb. 16, 2005, the disclosures of which are incorporated herein by reference.

While the high-side sensor **80** as described herein may provide compressor current information, the protection and control system **14** may also include a discharge pressure sensor **92** mounted in a discharge pressure zone and/or a temperature sensor **94** mounted within or near the compressor shell **15** such as within the discharge fitting **24** (FIG. 2). The temperature sensor **94** may additionally or alternatively be positioned external of the compressor **10** along a conduit **103** extending generally between the compressor **10** and the condenser **70** (FIG. 3) and may be disposed in close proximity to an inlet of the condenser **70**. Any or all of the foregoing sensors may be used in conjunction with the high-side sensor **80** to provide the protection and control system **14** with additional system information.

The low-side sensor **82** generally provides diagnostics related to low-side faults such as a low charge in the refrigerant, a plugged orifice, an evaporator fan failure, or a leak in the compressor **10**. The low-side sensor **82** may be disposed proximate to the discharge fitting **24** or the discharge passage **52** of the compressor **10** and monitors a discharge-line temperature of a compressed fluid exiting the compressor **10**. In addition to the foregoing, the low-side sensor **82** may be disposed external from the compressor

shell 15 and proximate to the discharge fitting 24 such that vapor at discharge pressure encounters the low-side sensor 82. Locating the low-side sensor 82 external of the shell 15 allows flexibility in compressor and system design by providing the low-side sensor 82 with the ability to be readily adapted for use with practically any compressor and any system.

While the low-side sensor 82 may provide discharge-line temperature information, the protection and control system 14 may also include a suction pressure sensor 96 or a low-side temperature sensor 98, which may be mounted proximate to an inlet of the compressor 10 such as the inlet fitting 26 (FIG. 2). The suction pressure sensor 96 and low-side temperature sensor 98 may additionally or alternatively be disposed along a conduit 105 extending generally between the evaporator 72 and the compressor 10 (FIG. 3) and may be disposed in close proximity to an outlet of the evaporator 72. Any or all of the foregoing sensors may be used in conjunction with the low-side sensor 82 to provide the protection and control system 14 with additional system information.

While the low-side sensor 82 may be positioned external to the shell 15 of the compressor 10, the discharge temperature of the compressor 10 can similarly be measured within the shell 15 of the compressor 10. A discharge core temperature, taken generally at the discharge fitting 24, could be used in place of the discharge-line temperature arrangement shown in FIG. 2. A hermetic terminal assembly 100 may be used with such an internal discharge temperature sensor to maintain the sealed nature of the compressor shell 15.

The liquid-line temperature sensor 84 may be positioned either within the condenser 70 or positioned along a conduit 102 extending generally between an outlet of the condenser 70 and the expansion valve 74. In this position, the temperature sensor 84 is located in a position within the refrigeration system 12 that represents a liquid location that is common to both a cooling mode and a heating mode if the refrigeration system 12 is a heat pump.

Because the liquid-line temperature sensor 84 is disposed generally near an outlet of the condenser 70 or along the conduit 102 extending generally between the outlet of the condenser 70 and the expansion valve 74, the liquid-line temperature sensor 84 encounters liquid refrigerant (i.e., after the refrigerant has changed from a vapor to a liquid within the condenser 70) and therefore can provide an indication of a temperature of the liquid refrigerant to the processing circuitry 88. While the liquid-line temperature sensor 84 is described as being near an outlet of the condenser 70 or along a conduit 102 extending between the condenser 70 and the expansion valve 74, the liquid-line temperature sensor 84 may also be placed anywhere within the refrigeration system 12 that would allow the liquid-line temperature sensor 84 to provide an indication of a temperature of liquid refrigerant within the refrigeration system 12 to the processing circuitry 88.

The ambient temperature sensor or outdoor/ambient temperature sensor 86 is located external from the compressor shell 15 and generally provides an indication of the outdoor/ambient temperature surrounding the compressor 10 and/or refrigeration system 12. The outdoor/ambient temperature sensor 86 may be positioned adjacent to the compressor shell 15 such that the outdoor/ambient temperature sensor 86 is in close proximity to the processing circuitry 88 (FIG. 2). Placing the outdoor/ambient temperature sensor 86 in close proximity to the compressor shell 15 provides the processing circuitry 88 with a measure of the temperature generally adjacent to the compressor 10. Locating the outdoor/ambient

temperature sensor 86 in close proximity to the compressor shell 15 not only provides the processing circuitry 88 with an accurate measure of the surrounding air around the compressor 10, but also allows the outdoor/ambient temperature sensor 86 to be attached to or within the electrical enclosure 28.

The processing circuitry 88 receives sensor data from the high-side sensor 80, low-side sensor 82, liquid-line temperature sensor 84, and outdoor/ambient temperature sensor 86. 10 As shown in FIGS. 4 and 5, the processing circuitry 88 may use the sensor data from the respective sensors 80, 82, 84, 86 to determine non-measured operating parameters of the compressor 10 and/or refrigeration system 12.

The processing circuitry 88 determines the non-measured 15 operating parameters of the compressor 10 and/or refrigeration system 12 based on the sensor data received from the respective sensors 80, 82, 84, 86 without requiring individual sensors for each of the non-measured operating parameters. The processing circuitry 88 is able to determine 20 a condenser temperature (T_{cond}), subcooling of the refrigeration system 12, a temperature difference between the condenser temperature and outdoor/ambient temperature (TD), and a discharge superheat of the refrigeration system 12.

25 The processing circuitry 88 may determine the condenser temperature by referencing compressor power on a compressor map. The derived condenser temperature is generally the saturated condenser temperature equivalent to the discharge pressure for a particular refrigerant. The condenser temperature should be close to a temperature at a mid-point of the condenser 70. Using a compressor map to determine the condenser temperature provides a more accurate representation of the overall temperature of the condenser 70 when compared to a condenser temperature value 30 provided by a temperature sensor mounted on a coil of the condenser 70 as the condenser coil likely includes many parallel circuits having different temperatures.

FIG. 6 is an example of a compressor map showing 40 compressor current versus condenser temperature at various evaporator temperatures (T_{evap}). As shown, current remains fairly constant irrespective of evaporator temperature. Therefore, while an exact evaporator temperature can be determined by a second degree polynomial (i.e., a quadratic function), for purposes of control, the evaporator temperature 45 can be determined by a first degree polynomial (i.e., a linear function) and can be approximated as roughly 45, 50, or 55 degrees Fahrenheit. The error associated with choosing an incorrect evaporator temperature is minimal when determining the condenser temperature. While compressor current is shown, compressor power and/or voltage may be used 50 in place of current for use in determining condenser temperature. Compressor power may be determined based on the current drawn by motor 32, as indicated by the high-side sensor 80.

55 Once the compressor current is known and is adjusted for voltage based on a baseline voltage contained in a compressor map (FIG. 6), the condenser temperature may be determined by comparing compressor current with condenser temperature using the graph shown in FIG. 6. The above 60 process for determining the condenser temperature is described in assignee's commonly-owned U.S. patent application Ser. No. 11/059,646 filed on Feb. 16, 2005, the disclosure of which is herein incorporated by reference.

Once the condenser temperature is known, the processing 65 circuitry 88 is then able to determine the subcooling of the refrigeration system 12 by subtracting the liquid-line temperature as indicated by the liquid-line temperature sensor

84 from the condenser temperature and then subtracting an additional small value (typically 2-3° F.) representing the pressure drop between an outlet of the compressor 10 and an outlet of the condenser 70. The processing circuitry 88 is therefore able to determine not only the condenser temperature but also the subcooling of the refrigeration system 12 without requiring an additional temperature sensor for either operating parameter.

The processing circuitry 88 is also able to calculate a temperature difference (TD) between the condenser 70 and the outdoor/ambient temperature surrounding the refrigeration system 12. The processing circuitry 88 is able to determine the condenser temperature by referencing either the power or current drawn by the compressor 10 against the graph shown in FIG. 6 without requiring a temperature sensor to be positioned within the condenser 70. Once the condenser temperature is known (i.e., derived), the processing circuitry 88 can determine the temperature difference (TD) by subtracting the ambient temperature as received from the outdoor/ambient temperature sensor 86 from the derived condenser temperature.

The discharge superheat of the refrigeration system 12 can also be determined once the condenser temperature is known. Specifically, the processing circuitry 88 can determine the discharge superheat of the refrigeration system 12 by subtracting the condenser temperature from the discharge-line temperature. As described above, the discharge-line temperature may be detected by the low-side sensor 82 and is provided to the processing circuitry 88. Because the processing circuitry 88 can determine the condenser temperature by referencing the compressor power against the graph shown in FIG. 6, and because the processing circuitry 88 knows the discharge-line temperature based on information received from the low-side sensor 82, the processing circuitry 88 can determine the discharge superheat of the compressor 10 by subtracting the condenser temperature from the discharge-line temperature.

As described above, the protection and control system 14 receives sensor data from the high-side sensor 80, low-side sensor 82, liquid-line temperature sensor 84, and outdoor/ambient temperature sensor 86, and derives non-measured operating parameters of the compressor 10 and/or refrigeration system 12 such as condenser temperature, subcooling of the refrigeration system 12, a temperature difference between the condenser 70 and outdoor/ambient temperature, and discharge superheat of the refrigeration system 12, without requiring individual sensors for each of the derived parameters. Therefore, the protection and control system 14 not only reduces the complexity of the compressor and refrigeration system, but also reduces costs associated with monitoring and diagnosing the compressor 10 and/or refrigeration system 12.

Once the processing circuitry 88 has received the sensor data and determined the non-measured operating parameters, the processing circuitry 88 can diagnose the compressor 10 and refrigeration system 12. As shown in FIGS. 4 and 5, the processing circuitry 88 is able to categorize a fault based on specific information received from the individual sensors and calculated non-measured operating parameters.

As shown in FIG. 4, once the processing circuitry 88 receives the sensor data and determines the non-measured operating parameters, the processing circuitry 88 can differentiate between specific low-side and high-side faults experienced by the compressor 10 and/or refrigeration system 12. Low-side faults may include a low charge condition, a low evaporator air flow condition, and/or a flow restriction at either or both of the condenser 70 and evaporator 72. A

high-side fault may include a high-charge condition, a non-condensable condition (i.e., air in the refrigerant), and a low condenser air flow condition.

By way of example, the processing circuitry 88 may be able to determine that the compressor 10 and/or refrigeration system 12 is experiencing a low-charge condition if the discharge superheat of the refrigeration system 12 is increasing relative to a predetermined target stored within the processing circuitry 88 while both the subcooling and the condenser temperature difference (i.e., condensing temperature minus outdoor/ambient temperature) are decreasing relative to a predetermined target stored in the processing circuitry 88.

By way of another example, the processing circuitry 88 may be able to determine that the compressor 10 and/or refrigeration system 12 is experiencing a high-side fault such as a high charge condition if the subcooling of the refrigeration system 12 and the temperature difference (i.e., condensing temperature minus outdoor/ambient temperature) are each increasing relative to a predetermined target stored in the processing circuitry 88 while the discharge superheat of the refrigeration system 12 remains relatively unchanged relative to a predetermined target stored in the processing circuitry 88 for a thermal expansion valve/electronic expansion valve flow control system or decreases relative to a predetermined target stored in the processing circuitry 88 for an orifice flow control system.

High-efficiency systems tend to employ larger condenser coils, which tend to require less subcooling (i.e., less liquid in the condenser coil, in percentage, when compared to a smaller condenser coil) relative to the condenser temperature difference to deliver optimum charge, therefore both subcooling and condenser temperature difference can be used for a more precise charge verification. Therefore, the ratio of subcooling over condenser temperature difference may be used to check both subcooling and condenser temperature difference. This ratio may be pre-programmed as a target value in processing circuitry 88. The ratio of subcooling over condenser temperature difference is a function of efficiency and may be used to verify charge (FIGS. 16 and 17). For example, the efficiency for a standard refrigeration system may be 0.6, the efficiency for a mid-level refrigeration system may be 0.75, and the efficiency for a high-efficiency refrigeration system may be 0.9. Such target ratios may be programmed into the processing circuitry 88 to confirm proper operation of the refrigeration system (FIG. 19).

The various other low-side faults and high-side faults that may be determined by the processing circuitry 88 are shown in FIG. 4, where increasing parameters are identified by an upwardly pointing arrow, decreasing parameters are identified by a downwardly pointing arrow, and constant (i.e., unchanged) parameters are identified by a horizontal arrow.

While the protection and control system 14 is useful in diagnosing the compressor 10 and/or refrigeration system 12 by differentiating between various low-side faults and high-side faults during operation of the compressor 10 and refrigeration system 12, the protection and control system 14 may also be used during installation of the compressor 10 and/or refrigeration system 12. As noted in FIG. 4, the protection and control system 14 may be used to diagnose each of the low-side faults and high-side faults with the exception of a low condenser air-flow condition at installation. Such information is valuable during installation to ensure that the compressor 10 and respective components of the refrigeration system 12 are properly installed and functioning within acceptable limits.

11

As indicated in FIG. 4, each of the low-side faults are monitored by the protection and control system 14 on an on-going basis, while the only high-side fault monitored by the protection and control system 14 on an on-going basis is the low condenser-air-flow condition. The high-charge condition is typically not measured on an on-going basis by the protection and control system 14, as the charge of the system is generally set at installation. In other words, the charge of the refrigeration system 12 cannot be increased without physically supplying the system 12 with additional refrigerant. Therefore, the need for monitoring a high-charge condition after installation is generally unnecessary except when additional refrigerant is added to the refrigeration system 12. The protection and control system 14 does not typically monitor the non-condensables high-side fault on an on-going basis because air is not usually injected into the refrigerant once the refrigerant is added to the refrigeration system 12. Air is only added into the refrigeration system 12 when a supply of refrigerant used to charge the refrigeration system 12 is contaminated with air.

While monitoring the high-charge condition and non-condensables condition are described as not being monitored on an on-going basis, each parameter may be monitored on an on-going basis by the protection and control system 14 to continually monitor the condition of the refrigerant disposed within the compressor 10 and/or refrigeration system 12.

Once the processing circuitry 88 has received the sensor data and has derived the non-measured operating parameters, the processing circuitry 88 can use the sensor data and non-measured operating parameters to derive performance data regarding operation of the compressor 10 and/or refrigeration system 12. With reference to FIG. 5, a flow chart is provided detailing how the processing circuitry 88 can derive a coil capacity of the evaporator 72 and an efficiency of the refrigeration system 12.

The processing circuitry 88 first receives sensor data from the high-side sensor 80, low-side sensor 82, liquid-line temperature sensor 84, and outdoor/ambient temperature sensor 86. Once the sensor data is received, the processing circuitry 88 uses the sensor data to derive the non-measured operating parameters such as subcooling of the refrigeration system 12, discharge superheat, and condenser temperature at 83.

The processing circuitry 88 can determine the condenser temperature by referencing an approximated evaporator temperature (i.e., at 45 degrees F., 50 degrees F., or 55 degrees F.) against the current drawn by the compressor, as previously described. A plot of current versus condenser temperature may be used to reference an approximated evaporator temperature against current information received from the high-side sensor 80 (FIG. 6). By using a plot as shown in FIG. 6, the processing circuitry 88 can determine the condenser temperature by referencing current information received from the high-side sensor 80 against the approximated evaporator temperature values to determine the condenser temperature.

Once the condenser temperature is determined, the processing circuitry 88 can then reference a plot as shown in FIG. 7 to determine the exact evaporator temperature based on discharge temperature information received from the low-side sensor 82. Once both the condenser temperature and the evaporator temperature are known, the processing circuitry 88 can then determine the compressor capacity and flow.

The discharge superheat may be determined by subtracting the condenser temperature from the discharge-line temperature, as indicated by the low-side sensor 82. Once the

12

discharge superheat is determined, the processing circuitry 88 can determine the suction superheat by referencing a plot as shown in FIG. 8. Specifically, the suction superheat may be determined by referencing the discharge superheat against the ambient temperature as indicated by the outdoor/ambient temperature sensor 86.

In addition to deriving the condenser temperature, evaporator temperature, subcooling, discharge superheat, compressor capacity and flow, and suction superheat, the processing circuitry 88 may also measure or estimate the fan power of the condenser fan 76 and/or evaporator fan 78 and derive a compressor power factor for use in determining the efficiency of the refrigeration system 12 and the capacity of the evaporator 72. The fan power of the condenser fan 76 and/or evaporator fan 78 may be directly measured by sensors 85 associated with the fans 76, 78 or may be estimated by the processing circuitry 88.

Once the non-measured operating parameters are determined, the performance of the compressor 10 and refrigeration system 12 can be determined at 87. The processing circuitry 88 uses compressor capacity and flow and suction superheat to determine a coil capacity of the evaporator 72 at 89. Because the processing circuitry 88 uses the fan power of the condenser fan 76 and/or evaporator fan 78 in determining the capacity of the evaporator 72, the processing circuitry 88 is able to adjust the capacity of the evaporator 72 based on an estimated heat of the condenser fan 76 and/or evaporator fan 78. In addition, because the compressor capacity and flow is determined using the suction superheat, the capacity of the evaporator 72 may also be adjusted based on suction-line heat gain.

Once the capacity of the evaporator 72 is determined, the efficiency of the refrigeration system 12 can be determined using the capacity of the evaporator 72 along with the fan power and compressor power factor at 91. Specifically, the processing circuitry 88 divides the capacity of the evaporator 72 by the sum of the compressor power and fan power. Dividing the capacity of the evaporator 72 by the sum of the fan power and compressor power provides an indication of the energy efficiency of the refrigeration system 12.

The energy efficiency of the refrigeration system 12 may be used to diagnose the compressor 10 and/or refrigeration system 12 by plotting the determined energy efficiency rating for the refrigeration system 12 against a base energy efficiency rating to determine a fault condition (FIG. 9). If the determined energy efficiency rating of the refrigeration system 12 deviates from the base energy efficiency rating, the processing circuitry 88 can determine that the refrigeration system 12 is operating outside of predetermined limits. Because operation of the refrigeration system 12 varies with changing outdoor/ambient temperatures, the energy efficiency rating is plotted against the outdoor/ambient temperature to account for changes in the outdoor/ambient temperature and its affect on the refrigeration system 12.

In addition to driving the energy efficiency of the refrigeration system 12, the processing circuitry 88 can also determine the load experienced by the refrigeration system 12 (i.e., kilowatt hours per day). As shown in FIG. 12, the processing circuitry 88 can determine the house load based on the capacity of the evaporator 72 and the run time of the compressor 10 (i.e., BTU per hour multiplied by run time (in hours) equals BTU load). This information, in combination with the run time of the compressor 10, may be used by the processing circuitry 88 to determine the overall load of the refrigeration system 12, and can be used by the processing circuitry 88 to diagnose the compressor 10 and/or refrigeration system 12.

13

Once the capacity is derived, the processing circuitry 88 may then also derive the evaporator air flow (i.e., air flow through the evaporator 72) as shown in FIG. 18 based on a pre-determined table located in non-volatile memory of the processing circuitry 88. The processing circuitry 88 relates the capacity or evaporator temperature to air flow as a function of outdoor ambient and indoor room dry-bulb and wet-bulb temperatures (i.e., humidity).

Specifically, the processing circuitry 88 may receive the outdoor temperature from the outdoor temperature sensor 86 and may receive the wet-bulb and/or room humidity from a thermostat. The thermostat may communicate the wet-bulb temperature and/or room humidity to the processing circuitry 88 through digital serial communication. Alternatively, the wet-bulb temperature and room humidity can be manually input by a user. Once the outdoor ambient temperature and indoor wet-bulb temperatures are known, the processing circuitry 88 can reference the outdoor temperature and wet-bulb temperature on a performance map stored in the processing circuitry 88 to determine the air flow through the evaporator 72. The performance map may include pre-programmed capacity and/or evaporator temperature information as it relates to outdoor ambient temperature, wet-bulb temperature, and air flow. Verifying evaporator air flow may be used to confirm proper installation and system capacity.

As described, the protection and control system 14 uses the various sensor data and derived non-measured operating parameters to monitor and diagnose operation of the compressor 10 and/or refrigeration system 12. The sensor data received from the high-side sensor 80, low-side sensor 82, liquid-line temperature sensor 84, and outdoor/ambient temperature sensor 86 may be used by the processing circuitry 88 to differentiate between various fault areas to diagnose the compressor 10 and/or refrigeration system 12. FIG. 11 details various fault areas and diagnostics that the processing circuitry 88 can differentiate between based on sensor data received from the high-side sensor 80, low-side sensor 82, liquid-line temperature sensor 84, and outdoor/ambient temperature sensor 86.

For example, the processing circuitry 88 relies on information from the high-side sensor 80 and low-side sensor 82 to determine compressor faults such as a locked rotor, a motor failure, or insufficient pumping, while the processing circuitry 88 relies on information from the high-side sensor 80, low-side sensor 82, and liquid-line temperature sensor 84 to distinguish between high-side system faults such as cycling on protection (i.e., cycling under a tripped condition), low air-flow through the condenser 70, and an overcharged condition.

FIG. 12 further illustrates how the processing circuitry 88 is able to distinguish between high-side faults and low-side faults using discharge superheat. As described above, the discharge superheat is a derived parameter and is calculated based on information received from the high-side sensor 80 and low-side sensor 82. The processing circuitry 88 compares the discharge superheat with the condenser temperature difference to differentiate between various high-side faults such as an overcharged condition or a non-condensable condition and various low-side faults such as low air-flow through the evaporator 72 or a low-charge condition. The processing circuitry 88 is not only able to derive non-measured operating parameters, but is also able to use the non-measured operating parameters and the sensor data to diagnose the compressor 10 and refrigeration system 12.

Receiving sensor data and deriving non-measured operating parameters allows the protection and control system 14

14

to monitor and diagnose the compressor 10 and refrigeration system 12 during operation. In addition to diagnosing the compressor 10 and refrigeration system 12 during operation, the protection and control system 14 can also use the sensor data and the non-measured operating parameters during installation of the compressor and individual components of the refrigeration system 12 (i.e., condenser 70, evaporator 72, and expansion device 74) to ensure that the compressor 10 and individual components of the refrigeration system 12 are properly installed.

With reference to FIG. 13, an exemplary flow chart is provided detailing an installation check used by the protection and control system 14 during installation of the compressor 10 and/or components of the refrigeration system 12. 15 Once the compressor 10 is installed into the refrigeration system 12, the compressor 10 is stabilized at 104. Once the compressor 10 is stabilized, the processing circuitry 88 receives sensor data from the high-side sensor 80, low-side sensor 82, liquid-line temperature sensor 84, and outdoor/ 20 ambient temperature sensor 86 at 106. As described above, the processing circuitry 88 uses the sensor data from the high-side sensor 80, low-side sensor 82, liquid-line temperature sensor 84, and outdoor/ambient temperature sensor 86 to derive non-measured operating parameters at 108. The 25 non-measured operating parameters include, but are not limited to, condenser temperature, subcooling of the refrigeration system 12, condenser temperature difference (i.e., condenser temperature minus outdoor/ambient temperature), and discharge superheat of the refrigeration system 12. 30 This information is used at an installation check 110 to determine whether the compressor 10 and various components of the refrigeration system 12 are properly installed.

Original equipment manufacturing data (OEM Data) such as size, type, condenser coil pressure drop, compressor maps, and/or subcooling targets for refrigeration system components such as the expansion device 74 are input into the processing circuitry 88 to assist with the installation check 110. For example, tables of capacity as a function of indoor air flow (i.e., air flow through the evaporator 72) and 40 indoor and outdoor temperatures may also be pre-programmed into the processing circuitry 88. The processing circuitry 88 can use this information, for example, to adjust a subcooling calculation made by reading a pressure at an outlet of the condenser 73 to account for a pressure drop 45 through the condenser 73. This information is used by the processing circuitry 88 to determine whether the components of the refrigeration system 12 are operating within predetermined limits.

With reference to FIG. 14, the processing circuitry 88 first 50 calculates the energy efficiency rating of the refrigeration system 12 and plots the energy efficiency rating versus the outdoor/ambient temperature as provided by the outdoor/ambient temperature sensor 86 at 114. The processing circuitry 88 compares the calculated energy efficiency rating 55 versus a base energy efficiency rating (FIG. 9) to determine if a fault exists at 116. If the energy efficiency rating is within an acceptable range such that the energy efficiency rating is sufficiently close to the base efficiency rating, the processing circuitry stores the value of the energy efficiency rating at 118. If the processing circuitry 88 determines a fault condition exists, the processing circuitry 88 calculates a new energy efficiency rating after the fault started at 120.

The processing circuitry 88 is able to track the energy efficiency of the refrigeration system 12 by generating an efficiency index at 122. The processing circuitry 88 generates the efficiency index by dividing the current efficiency by the last stored reference at the same outdoor/ambient tem-

15

perature. This way, the processing circuitry 88 is able to track the change in efficiency of the refrigeration system 12 over time at the same outdoor/ambient temperature.

Once the installation check 110 is complete, the protection and control system 14 then determines the refrigerant charge within the refrigeration system 12, as well as the air flow through the condenser 70 and evaporator 72. With reference to FIG. 15, a flowchart detailing a process for determining the refrigerant charge is provided. The processing circuitry 88 first determines the initial charge within the refrigeration system 12 and the air flow through the condenser 70 and evaporator 72 at 124. Once the initial charge and air flow are determined, the processing circuitry 88 then calculates the capacity and energy efficiency rating of the refrigeration system 12 at 126.

The capacity and energy efficiency rating are compared to baseline values to determine whether the refrigeration system 12 contains a predetermined amount of refrigerant. If the capacity and/or energy efficiency rating indicates that the refrigeration system 12 is either undercharged or overcharged, the processing circuitry 88 indicates that either more charge or less charge is required at 128. Once the capacity and energy efficiency rating indicate that the refrigeration system 12 is properly charged, the level of refrigerant and airflow through the condenser 70 and evaporator 72 is verified by the processing circuitry 88 at 130.

Once the compressor 10 and components of the refrigeration system 12 are properly installed and the charge and air flow are verified, the protection and control system 14 is able to diagnose the compressor 10 and/or refrigeration system 12 at 132. The protection and control system 14 ensues active protection of the compressor 10 and/or refrigeration system 12 at 134, indicating that the installation is complete at 136. During operation of the compressor 10 and refrigeration system 12, the protection and control system 14 provides alerts and data at 138 indicative of operation of the compressor 10 and/or refrigeration system 12.

The protection and control system 14 is able to receive sensor data and determine non-measured operating parameters of a compressor and/or refrigeration system to reduce the overall number of sensors required to adequately protect and diagnose the compressor and/or refrigeration system. In so doing, the protection and control system 14 reduces costs associated with monitoring and diagnosing a compressor and/or a refrigeration system and simplifies such monitoring and diagnostics by driving virtual sensor data from a limited number of sensors.

What is claimed is:

1. A system comprising:
a compressor operable in a refrigeration circuit;
an ambient temperature sensor producing a signal indicative of an ambient temperature; and
processing circuitry calculating a plurality of energy efficiency ratings of said refrigeration circuit for a plurality of ambient temperatures, generating a first plot of said plurality of calculated energy efficiency ratings versus said plurality of ambient temperatures and comparing said first plot to a second plot of a plurality of base energy efficiency ratings versus said plurality of ambient temperatures to determine if a fault condition exists.
2. The system of claim 1, wherein said processing circuitry determines whether said refrigeration circuit is operating within an acceptable range based on said comparison of said first plot and said second plot.

16

3. The system of claim 1, wherein said processing circuitry stores said plurality of calculated energy efficiency ratings.

4. The system of claim 3, wherein said processing circuitry generates an efficiency index by dividing a calculated energy efficiency rating for a particular ambient temperature by a previously stored value of said calculated energy efficiency rating for said particular ambient temperature.

5. The system of claim 4, wherein said processing circuitry tracks changes in efficiency of said refrigeration circuit over time based on said efficiency index.

6. The system of claim 1, wherein said processing circuitry tracks a change in said plurality of calculated energy efficiency ratings over time.

7. The system of claim 1, wherein said processing circuitry determines a charge of said refrigeration circuit based on said comparison of said first plot to said second plot.

8. A system comprising:
a compressor operable in a refrigeration circuit;
an ambient temperature sensor producing a signal indicative of an ambient temperature; and
processing circuitry calculating an energy efficiency rating of said refrigeration circuit, said processing circuitry generating an efficiency index by dividing said calculated energy efficiency rating by a most recently stored value of said calculated energy efficiency rating for a particular ambient temperature to determine changes in efficiency of said refrigeration circuit over time.

9. The system of claim 8, wherein said processing circuitry generates a relationship of said calculated energy efficiency rating and said ambient temperature.

10. The system of claim 9, wherein generating said relationship of said calculated energy efficiency rating and said ambient temperature includes generating a first plot of said calculated energy efficiency rating versus said ambient temperature.

11. The system of claim 10, wherein said processing circuitry compares said calculated energy efficiency rating to a base energy efficiency rating.

12. The system of claim 11, wherein comparing said calculated energy efficiency rating to said base energy efficiency rating includes comparing said first plot of said calculated energy efficiency rating versus said ambient temperature to a second plot of said base energy efficiency rating versus said ambient temperature.

13. The system of claim 12, wherein said processing circuitry determines whether said calculated energy efficiency rating is within an acceptable range based on said comparison of said first plot and said second plot.

14. The system of claim 8, wherein said processing circuitry determines whether said calculated energy efficiency rating is within an acceptable range based on a comparison of said calculated energy efficiency rating and a base energy efficiency rating.

15. The system of claim 11, wherein said processing circuitry determines a charge of said refrigeration circuit based on said comparison of said calculated energy efficiency rating to said base energy efficiency rating.

16. A method comprising:
producing a signal indicative of an ambient temperature;
calculating by processing circuitry a plurality of energy efficiency ratings of a refrigeration circuit for a plurality of ambient temperatures;
generating by said processing circuitry a first plot of said plurality of calculated energy efficiency ratings versus said plurality of ambient temperatures;

17

comparing by said processing circuitry said first plot to a second plot of a plurality of base energy efficiency ratings versus said plurality of ambient temperatures; and determining by said processing circuitry if a fault condition exists based on said comparison. 5

17. The method of claim **16**, further comprising generating an efficiency index by dividing a calculated energy efficiency rating for a particular ambient temperature by a previously stored value of said calculated energy efficiency 10 rating for said particular ambient temperature to determine changes in efficiency of said refrigeration circuit over time.
